BOTTLE HANDLING RACK

Adrian B. Scott, Anaheim, Calif., assignor to Vita Pakt
Citrus Products, Covina, Calif., a corporation of California

Filed Aug. 15, 1962, Ser. No. 71,300

Term of patent 14 years

(Cl. D80—9)

FIGURE 1 is a side perspective view of the bottle handling rack, showing my new design with shelves being in a raised position.

I claim:

The ornamental design for a bottle handling rack, as shown and described.
